UNITED STATES PATENT OFFICE.

JAMES W. SMALLMAN, OF BLACKDOWN, NEAR LEAMINGTON, ENGLAND.

HAULAGE-CLIP.

1,077,436.

Specification of Letters Patent.

Patented Nov. 4, 1913.

Application filed August 14, 1911. Serial No. 643,997.

To all whom it may concern:

Be it known that I, JAMES WILLIAM SMALLMAN, a subject of the King of Great Britain and Ireland, residing at Blackdown, 5 near Leamington, in the county of Warwick, England, have invented a new and useful Haulage-Clip, of which the following is a specification.

The accompanying drawings illustrate a 10 clip constructed according to the present invention.

Figure 1 is a side elevation of the clip. Fig. 2 represents the inner surface of the left-hand shell; the dotted lines indicating 15 the position of the back of the head of the lever and the wedge-like continuation when the handle is raised to the full extent. Fig. 3 is a view of the inner surface of the right-hand shell. Fig. 4 is a separate view of the 20 head and body of the lever. Fig. 5 is a corresponding plan. Fig. 6 is a vertical section through the shells on the line $\alpha\alpha$ in Fig. 1 (looking in the direction of the arrow—the coupling being omitted), showing 25 an adjustable "ball" and "cup" device flush at both ends. Fig. 7 is a separate view of the adjustable device.

This clip comprises two rocking shells, a 30 central adjustable device for loosely connecting the shells and a lever furnished with a trunnion-peg; the head of the lever working along inclines on the upper parts of the shells. The coupling for effecting attachment to the drawbar of the tub or wagon is 35 secured to the clip by a pin and split cotter.

The adjustable devices generally used are 40 claimed in the specification to my United States Letters Patent No. 728421, granted May 19, 1903; the special hooked spring for holding open the jaws to facilitate the placing of the clip over the rope being claimed in the specification to my United States Letters Patent No. 941049, granted Nov. 23, 45 1909.

After the clip has been caused to grip the 50 rope by the depression of the handle of the lever, the head of the lever arrives against two stops at the ends of the inclines; the downward movement of the handle being thus limited. The exact height of the handle above the rope is of great importance. These two stops (by keeping the upper parts of the shells away from each other) interfere with the opening of the

55 jaws to release the rope; and are therefore no longer than is absolutely necessary. When worn, they are a source of trouble; and, further, the abutting edges on the head of the lever are sharp and tend to run harshly along the inclines. The inclines 60 are now made without stops for the head of the lever; but stops extend laterally from the body of the lever and bed against the shells below the front projections. These stops, though large and strong, leave plenty 65 of room for the catch that locks the lever. The back of the head of the lever corresponds in size and shape with the head of the superseded lever; but there is a wedge-like continuation that gives a smoother ac- 70 tion on the inclines. When the lever is in its lowest position, this continuation does not touch the shells.

The adjustable device is reversible, so that, 75 when the curve-rollers are all on one side of the rope, the flush end of that device can be on the same side. Sometimes, however, there are curve-rollers on each side of the rope; and then an adjustable device flush at both ends is desirable. To obtain such a device, 80 I dispense with the trunnion-collar, slightly alter the bolt and retain the trunnion-nut. The bearing surface on the head of the bolt is of "ball" shape to match a shallow "cup" 85 formed on the boss of the shell. The bolt, which may have a square or hexagonal head, does not extend beyond the ribs of the shell; and has a round neck that turns in a hole in the boss. Near the "cup", the hole is round; but gradually becomes oval to permit the 90 shell to rock. The threaded end of the bolt engages with the trunnion-nut mounted in the opposite shell.

R is the right-hand shell, looking in the direction in which the rope travels; L being 95 the left-hand shell.

A is the central adjustable bolt having a bearing surface a of "ball" shape.

r is the shallow "cup" formed on the boss of the shell R.

B is the trunnion-nut into which the bolt A screws.

C is the lever with its large lateral stops C'; C $\times$ being the handle.

c is the trunnion-peg upon which the lever 105 C is pivoted.

c' is the back of the head of the lever and c $\times$ the wedge-like continuation.

The lever C is automatically locked by the catch D that turns on the joint-pin d. d' and d'' are the front projections.

E is the coupling attached to the clip by 5 the pin e.

F and F' are liners riveted in the jaws k and k'.

m and m' are holes in the shells R and L for the trunnion-peg c.

10 N and N' are the inclines (without stops) along which work the back c' and continuation c'' of the head of the lever C.

P is the hooked spring; p and p' being the recesses for the hooks.

15 I claim:

1. A haulage clip comprising a pair of rocking shells which have inclines without stops, a central adjustable device for connecting the shells consisting of a bolt having 20 a bearing surface of "ball" shape that matches a corresponding "cup" formed on the boss of one of the shells, the bolt screwing into a trunnion-nut mounted in the opposite shell, and a lever pivoted to act between the inclines, the lever being provided with stops extending laterally to bed against the fronts of the shells, substantially as described.

2. A haulage clip comprising a pair of 30 rocking shells having inclines without stops,

a central adjustable device connecting the shells and a lever pivoted to act between the inclines, the lever being provided with stops that extend laterally to bed against the fronts of the shells, substantially as de- 35 scribed.

3. A haulage clip comprising a pair of rocking shells with inclines, a lever pivoted to act between the inclines, and for connecting the shells a bolt having a bearing surface of "ball" shape that matches a corresponding "cup" formed on the boss of one 40 of the shells, the bolt screwing into a trunnion-nut mounted in the opposite shell, substantially as described.

4. In a haulage clip, the combination, with the rocking shells R and L which have inclines N and N', and the central bolt A that passes through a hole in one shell and screws into a trunnion-nut B mounted in the other 50 shell, of the lever C pivoted on the trunnion-peg c to act between the inclines N and N' and provided with stops C' extending laterally to bed against the fronts of the shells R and L, substantially as set forth.

JAMES W. SMALLMAN.
